ILLUSORY STAIRCASE

John P. Cahn, San Francisco, Calif.

Application April 2, 1949, Serial No. 85,110

12 Claims. (Cl. 272—8)

1

This invention relates to display apparatus and particularly is directed to a form of device usable for creating optical illusions especially desirable for advertising purposes.

In its essence the invention is directed to a device wherein recourse may be taken to units adapted to portray unusual and novel effects of such a nature that observers are tricked to believe elements actually not physically present are being worked with in the obtainment of fanciful results.

The invention herein to be described embodies an advertising device for displaying various objects or persons in unusual and abnormal positions relative thereto. In one form of the unit there is provided a rising section in the form of a staircase which is completely usable in its initial state in all respects. The staircase has positioned adjacent thereto a banister and a hand support railing which rises from the end of each step of the complete staircase. Between the staircase proper and the railing is a panel section to enclose the complete staircase and to provide the appearance of a solid section between the railing and the various steps comprising the staircase.

The staircase as it is constituted for utilization as an advertising medium is formed broadly into three separate sections of which the lowermost section and the uppermost section each comprise a plurality of steps fixedly supported relative to the hand railing and the paneling. A movable section comprising generally two or three steps of the complete staircase is positioned at an intermediate location between the top and the bottom of the staircase section as a whole. This movable step section is arranged and positioned so that in its unused state it normally so fastens or locks in place with respect to the fixed step section as to provide a staircase upon which those using the device for display or advertising purposes may readily walk up and down, and which may readily be examined by the looking audience to create the illusion which is to be formed. Fastening elements, usually positioned at the top and bottom of each handrail, as well as an intermediate point thereof which coincides with the position from which the movable step section is to be withdrawn from the main fixed top and bottom step section, are provided so that various arrangements of ropes, chains, wires, tapes or the like may be strung between these various fastening or connecting points. Such strung tapes or ropes or the like serve the purpose generally of preventing the looking audience

from moving up and down the steps during the time the illusions are produced and also serve for masking the motion of any movable parts relative to other parts of the device.

5 For display, illusory, advertising and generally related purposes the movable step section is arranged to slide inwardly or laterally with respect to the fixed step section. At the time that this lateral motion of the movable section is initiated 10 a reflecting member is positioned to move immediately in front of the space formerly occupied by the movable step section and closely adjacent the fixed section so as to be raised relative to the lowermost fixed step section so that the viewing 15 audience looking at the complete step section will see in the reflector the lowermost fixed step section which will then appear as if it were the now removed movable step section. The retraction of the movable step section and the elevation of the reflecting member provides in the complete staircase an opening intermediate the uppermost fixed step section and the rear surface of the reflector through which objects or persons may be moved relative to the reflecting body so as to project beyond the outer edge thereof and then to assume, as far as the looking audience is concerned, a position by which they appear to "float" or protrude above the step section as a whole, and thus actually give the appearance of having moved 20 outwardly and through a staircase section. By stringing ropes, tapes or the like between the fastening members it will be appreciated that the shadows and masking effects thereby introduced serve to hide or obscure the edge as well as any 25 motion of the reflecting member insofar as the looking audience is concerned.

In its general operation the movement of the movable step section initially is only that amount which is required to permit the reflecting body 40 to be moved between it and the lower fixed step section so that minimum opportunity of the looking audience to sense the removal initially of a portion of the complete staircase exists. After the reflecting member has been moved outwardly 45 to its extended position to reflect the lower fixed step section it is, of course, immaterial as to the extent of motion which is later given to the movable step section.

Generally the complete staircase section is 50 mounted or supported on a display platform. The sides of the staircase are enclosed so that a housing arrangement is formed by the staircase itself and by the enclosed sides. The movable step section is arranged to slide into the so-formed housing. If it be desired that the head

of a human being be caused to appear to extend outwardly and to be suspended above or to protrude from the staircase section itself the person or persons so to be exhibited are normally moved within the housing prior to the commencement of the exhibition. With the movement of the reflecting member outwardly and the movement of the movable step section inwardly into the housing an enlarged opening is formed intermediate the reflector and the upper fixed step section 10 so that the person can then move within the housing to a position such that the head, for instance, extends above the top of the reflecting member and appear to lookers as extending directly outwardly from or floating above the steps as a whole.

With these features in mind it becomes the primary object of this invention to provide a device for exhibition or advertising purposes by which optical illusions can be created to cause 20 an audience viewing the unit to observe particularly those objects or human beings with which the illusion mechanism is associated.

Other objects of the invention are those of providing a device for exhibition purposes wherein the components required are few and whereby a normally well-known device or instrumentality may be readily converted into a form of unit which serves to mystify and intrigue the looking audience.

Other objects and advantages of the invention will become apparent and at once suggest themselves to those skilled in the art to which the invention is directed upon reading the following description and claims in connection with the accompanying drawings wherein:

Fig. 1 is a schematic view to represent the staircase and the exhibition platform used thereby in its initial state prior to utilization for exhibition purposes;

Fig. 2 is a sectional view looking at a portion of the staircase section of Fig. 1 from the left and shows the fixed and movable step sections in position such as to form a normally solid staircase;

Fig. 3 is a view of the same general type as Fig. 2 showing the movable step section removed from the fixed step sections and the illusion creating reflector likewise moved to portray the presence of the fixed step section in a manner to simulate the movable section;

Fig. 4 is an enlarged section of a portion of Fig. 2 to indicate particularly the stair locking and moving mechanism;

Fig. 5 is a front view of a portion of the step section of Fig. 1 with ropes or tapes positioned with respect to the railing and paneling so that the movable step section may be slidably removed from the fixed step section with a minimum opportunity for discernment;

Fig. 6 is a sectional view of a portion of the paneling of Fig. 5 to illustrate particularly the location of the rope or tape fastening means with respect to the paneling;

Fig. 7 is an enlarged view of a portion of Fig. 6 to show in further detail the rope or tape fastening mechanism; and,

Fig. 8 is a detail of the rope fastening mechanism of Fig. 7 taken on the line 8-8 of Fig. 7 looking in the direction of the arrows.

Referring now to the drawings, for a further understanding of the invention, and first to Fig. 1, it will be seen that a staircase section 11 comprising a multiplicity of steps may be supported for exhibition purposes upon a platform 13. At

the lowermost end of the staircase 11 is a balustrade or banister 15 which is topped by a handrail 17 between which and the staircase proper are sections or paneling 19 each having grooved members 21 extending outwardly from the junction of the tread and riser section of each step of the staircase and the handrail. The direction of the grooves or slots is at an angle of substantially 45° to the horizontal tread section of each step and the vertical riser section of each step, or, in other words, in a direction coinciding with that of the bisector of the angle formed between the tread and riser section of each of the several steps. The outer section of the paneling 19 is likewise provided with similar grooves or slots 23, although, as will be apparent from an observation of Fig. 8, it is not essential or necessary that such grooves or slots originate at any particular locus relative to the step section. Side support members 25 and vertical upright supports 27 which serve to brace the complete step section are also provided as a part of the installation.

Additional paneling members 29, likewise grooved, fill the space between the side support 25 and the vertical supports 27 so as to form a housing and enclosure for the complete section with one outer surface of such housing being formed by the step section itself.

As can be noted particularly from Fig. 5, a tape or rope 30 may be drawn between the uppermost end of the railing 17 and across the steps. Likewise, at the bottom of the railing 17 an additional rope or tape 31 may be strung. At a point intermediate the top and bottom of each of the handrail sections 17 and within the groove or slot 32 extending outwardly to the handrail from the intersection of the riser element of the movable step section 34 and the tread section 35 of the lowermost fixed step section 36 there is a further fastening hook or the like 38, which is shown particularly in Figs. 6, 7 and 8. The hook 38 is carried in the groove or slot 32 and secured therein by means of the outer paneling section surfaces 19 with respect to the inner paneling sections 39 (see Fig. 8).

At times when the optical illusion is to be created, a demonstrator may secure a rope or tape 40 which is to be strung over and above the step section first, for instance, at one of the lower fastening elements on the rail 17 and such rope then, for instance, may be strung to follow the paths indicated by the arrows on Fig. 5 so as to wrap around the uppermost rope or tape 30 then downwardly to the lowermost fastening section on the opposite rail 17 and then to the hook or fastener 38 intermediate the length of the railing 17 and thence across to the corresponding hook 38 beneath the opposite railing section 17 from which it passes to the hook at the lowermost section of the right hand railing 17. Thus the horizontal or substantially horizontal tape or rope is now positioned at the uppermost edge of the groove or slot which is above the junction. Thus, the tape or rope 40 between the fasteners 38 is now positioned substantially parallel to the junction of the riser and tread sections 34 and 35 of the movable and fixed step sections 33 and 36.

At times when the movable step section is to be retracted to create the desired optical illusion provision must be made for unlocking this step section from its position relative to the fixed step section to form a usable staircase. The movable step section 33 is supported in the modi-

ification shown upon a pair of guide rails 40 and 41, supported at each end of the step section and while not shown may be carried or supported from the more rigid support member 25. In one form of the herein provided arrangement the movable step section 33 is arranged to slide on the guides 40 and 41 by roller contact with bearing elements 43. These elements are generally brass or other suitable metal having therein a groove extending circumferentially and into which groove rubber or other flexible material may be fitted to provide and insure substantially soundless lateral motion of the step section upon the guides. A stop 44 or the equivalent is usually arranged to limit the motion of the step section inwardly.

Locking of the movable step section in a position to make the staircase usable is provided by means of the arm 45 carrying a fastening detent element 46 which is arranged to hold against a recess 47 on the rear of the riser of the movable step section, for instance. Release of the movable step section for lateral movement within the housing is provided by any suitable means mechanical or manual to exert a slight pressure or pull upon the arm 45 to cause the arm to rotate slightly in a clockwise direction to cause the locking pin or detent 46 to move out of the recess 47 to the position indicated by dotted outline in Fig. 4 immediately to the left of the fixedly positioned step section. Such movement will permit the pin or detent 46 to rest into a second recess or slot 48 to hold the movable step section in a semi-permanently locked state relative to the fixed step section. Lateral movement of the step section 34, however, provides an opening between the fixed step section 35 and the movable step section 34 through which a reflector element 49 may be passed. The reflector 49 is of a length slightly in excess of the length of the steps by an amount necessary to permit it to fit within the grooved member 32 of the various grooves or slots 21 formed in the paneling 19 between the railing sections 17 and the steps 11.

All of Figs. 2, 3, 4 and 7 particularly represent the positioning of the reflecting member 49 relative to the steps 11 and to the mirror support groove 32. In Fig. 2 the reflector 49 is in its retracted position and resting upon its support 51, whereas in Fig. 3 the mirror or reflector 49 is shown in an extended position. To extend the reflector 49 outwardly from the position shown by Fig. 2 to that shown by Fig. 3 it can be seen that the counter-weight 50 will at the time the movable step section is drawn laterally into the housing serve to balance substantially the weight of the reflector so that slight pressure exerted against the reflector by downward pull on the counter-weight or an upward push on the reflector will cause the reflector to move in the space between the steps and along the grooved path 32 to that position which is indicated, for example, by each of Figs. 3 and 7.

The release of the movable step section from its locked position relative to the fixed step section where it forms the usable staircase is provided generally by means of a person conventionally represented at 52 located within the housing. Likewise, the same person usually moves the counter-weight 50 downwardly to bring the mirror or reflector 49 into its proper position for reflecting the lower fixed step section. At the time periods when the reflector 49 is moved to that position shown in Fig. 3, for

instance, the arm 45 is again moved downwardly from its position such that the detent and pin 46 are in semi-permanent locking position. This then will permit the movable step section to slide to the left from its position shown in Fig. 2 to that position shown in Fig. 3 with the counter weight 55 serving generally to balance the weight of the step section so that the person 52 within the cabinet will have no difficulty moving the steps 34 laterally. The position of the movable step section 34 to form a usable staircase, and later to permit outward motion of the mirror or reflector 49 to provide the maximum lateral shift relative to the housing and such as to bring the step section up against the stop 44 is represented particularly by the showing of Fig. 4 which is an enlarged section of that which is shown by each of Figs. 2 and 3 particularly.

It can be seen that with the movable step section retracted and drawn into the cabinet or housing, a reasonable amount of space exists to the left of the reflector 49 as it is shown in Fig. 3. This space is adequate to permit the person 52 located within the housing formed to the rear of the steps to assume a standing position, as in Fig. 3, in contrast to the crowded and sitting position in Fig. 2. At the same time the person housed within the cabinet is able to move through the opening now provided between the two fixed step sections (or where only a lower fixed step section exists, to the rear of the mirror) to a position such that the head 57, for instance, extends up and above the top of the mirror. To a looking audience viewing the staircase section from substantially the front, that person will then appear in the steps generally above the tape or rope extending transversely between the hooks 38 as suspended above the step section and located in one of the areas identified particularly between the various strung ropes or tapes.

The position of the mirror, in the position shown by Fig. 3, for instance, creates the illusion of the actual presence to the left of the mirror of the movable step section which has actually been removed. Because the looking audience sees in the mirror or reflector 49 from the front the image of the lower fixed step section appears in such a way that the tread sections of the fixed steps appear in the mirror as if they constituted the riser sections of the movable step section. It is usually preferable to have the mirror or reflector 49 of the front surface reflection type to improve the illusion, although this is not an essential factor of the invention and the normal rear surface reflecting mirror is also usable.

In staging a demonstration of the character necessary for the utilization of this invention as an advertising medium the person 52 positioned within the housing and who moves to such location that his head 57 protrudes beyond the edge of the mirror to appear as if suspended above the steps frequently may wish to create a further form of optical illusion and to appear as if rising still further above the steps. To this end the hooks 38 which fasten the tapes or ropes 40 are generally carried on a slider block 61 positioned in a recessed portion 62 of the main panel 63 located immediately behind the paneling surfaces 19 which provide the slots or grooves 21. The extent of this recess is to a very minor distance below the bottom edge of the handrailing 17 so that to the unsuspecting looking audience the ropes or tapes 40, when they are fastened, ap-

pear generally to extend outwardly from the bottom of the railing 17. It will be observed that with the mirror or reflector 49 in its extended position it moves to a position substantially adjacent the rope section 40 which extends parallel to the junction of the riser and tread sections of the steps. Thus it becomes necessary, if the head 57 of the exhibitor is to be moved upwardly, that the mirror also be moved upwardly to mask any motion of the exhibitor from behind the reflecting surface. Accordingly, by the exhibitor himself pulling slightly at the bottom of the mirror or reflector 49, it is possible now to move the mirror upwardly by a slight additional amount and use the upper surface of the mirror to push against the lowermost surface of the hook 38 and to move the hook and its fastening slider block 65 upwardly to a position substantially adjacent the lower side of the handrailing 17. This then lifts with it the rope or tape 40, but lifts it to such a limited degree as to be unobservable. The additional upward movement of the reflector 49 and the hook 38 is usually less than six inches, because greater amounts are apt to become observable to the looking audience. At these times, then, the person directing the performance may through the utilization of a magical wave of the hand to draw the attention of the audience away from the steps instantaneously indicate that the suspended head 57 can be raised still further, whereupon the person within the housing merely stands slightly more erect as will be permitted with concurrent raising of the reflector 49. Then, the appearance of the head floating slightly above the step section is enhanced.

When the invention is used for advertising purposes or the like it is particularly desirable that the demonstrators arrange the display programs in such a way that the attention of the looking audience is normally momentarily diverted from the apparatus itself at time periods of transition from one set of operational conditions to another. This would generally preclude all possibility that any observer would be able to sense the shifting of the mirror or reflector, for instance, or the change in position of the movable step section relative to the fixed steps. However, the actual programming and staging of demonstrations utilizing the equipment herein described forms, per se, no part of the invention itself and, therefore, is not herein described in further detail.

In the use of the invention as an advertising medium it is often particularly desirable that the unit be capable of ready dismantling so as to be easily shipped or moved from place to place. Accordingly, in the preferred embodiment of the invention the various component parts are usually so made and designed with respect to one another that the unit as a whole may be disassembled and packed in a compact form occupying but relatively little space and generally of a length not exceeding that of either the steps or the platform, in a case where the platform is not made in a folded state so that it can be readily folded back upon itself.

Various modifications may be made in the arrangements herein disclosed and therefore these arrangements must be generally considered as diagrammatic and representative of one form which the invention may assume.

One of these modifications might readily be that of providing only a single fixed step section together with the hereinabove described movable section. This would tend to make the complete stair section of a reduced length, but interesting

effects can nonetheless be achieved under such circumstances. With only a single fixed step unit it is usually desirable that the uppermost riser of the movable step section be of somewhat foreshortened height and that the staircase as a whole terminate in a flat or substantially flat platform or standing room surface above the movable step section. In this way the edge of the flat platform surface would then form the remaining portion of the normal riser of the uppermost step.

In another modification of the invention it is possible to avoid the inclusion of the paneling hereinbefore described, particularly with reference to the utilization of the panel section to guide and support the edge of the mirror. In instances where the panel is omitted it is usually desirable to have a row of balusters between the hand railing section and the ends of the steps. One of the balusters at each end of the steps may then be conveniently arranged to mask any motion of the mirror as it rises and likewise may, of itself, form the supporting medium for guiding the edge of the mirror or reflector.

Also, it will be understood that in some instances the movable section may be arranged in duplicate, triplicate, or in multiple, as desired. In these instances, of course, the operating mechanism for each movable unit may be generally similar and various objects or persons may be so positioned within the housing that at times when the various movable sections have been separated from the fixed sections and the reflectors or mirrors located, those objects or persons may be caused to appear as though floating above or suspended above the remaining fixed sections. Under these circumstances the plurality of fixed sections which will be used will portray or simulate the presence of each of the movable sections which have been displaced from the complete assembly.

The invention has herein been illustrated also as comprising step sections to form a complete staircase. It is, of course, apparent that various other formations may be substituted for the steps of the section so long as the arrangement is of generally symmetrical shape. The actual arrangement by which one could move from the lowermost portion of the display to the uppermost portion may be, where desired, in the form of an incline or ramp, or it may be in the form of an undulating surface in which the rises and horizontal extensions are substantially complementary to one another. Accordingly, within the meaning of the hereto appended claims it will be understood that generally a staircase section or a step section is to be regarded as terminology defining one or the other of such forms and that reference to the illustrated form of the invention will be regarded as defining generally other sections of surfaces usable for the purposes described.

Having now described the invention, what is claimed is:

1. A display unit comprising a staircase having a fixedly positioned step section and a movably positioned step section arranged normally to be positioned in substantially precise alignment with the fixed section to form a complete stair section, a support for housing the movable step section, a reflecting means supported to be moved between the fixed and movable step sections to reflect the fixed section and thereby to provide the illusion of presence of the movable section, and means for shifting the movable step section within the housing at a time when the reflecting

member is moved to its position intermediate the two sections, said shift of the movable section providing an opening behind the reflecting body through which objects may be moved to selected positions relative to each of the reflecting body and the step sections.

2. A display unit comprising a staircase having at least one fixedly positioned stair section including a plurality of individual steps and a movably positioned stair section also including a plurality of individual steps arranged normally to be positioned in substantially precise alignment with the fixed stair section, a housing for housing and supporting the movable step section, a reflecting means supported to be moved intermediate the tread section of the fixed stair section juxtaposed to the riser section of the movable stair section to reflect the tread sections of the fixed stair section and thereby to provide the illusion of presence of the movable section, and means for shifting the movable step section laterally within the housing at a time when the reflecting member is moved to its position intermediate the two sections, said lateral shift of the movable section providing an opening behind the reflecting body through which objects may be moved to selected positions relative to each of the reflecting body and the step sections.

3. A display unit comprising a staircase having a pair of positioned step sections and a movably positioned step section arranged normally to be positioned in substantially precise alignment with the fixed sections and intermediate thereof so as normally to form a continuous and usable staircase, a support beneath the step sections and serving as a housing for the movable step section, a reflecting means supported to be moved intermediate the fixed and movable step sections to reflect the fixed step section when viewed from the direction of the fixed section and thereby to provide the illusion of actual presence of the movable section, and means for shifting the movable step section laterally within the housing support at a time when the reflecting member is moved to its position intermediate the two step sections, said lateral shift of the movable section providing an opening in the housing behind the reflecting body through which objects may be moved to selected positions relative to each of the reflecting body and the step sections.

4. A display unit comprising a staircase formed of at least one fixed section and at least one movable section each in the form of steps and arranged to be brought into precise alignment with one another so as to provide a usable step section, a support housing of which the fixed stair section is arranged to form at least a portion of one outer surface and into which the movable stair section may be positioned, a reflecting element positioned and supported within the housing in a plane substantially intersecting adjacent tread and riser sections of the fixed and movable stair sections, respectively, means for moving the reflector element to a position such that it reflects the fixed stair section to give the illusion of the actual presence of the movable stair section, and guide and support means supported within the housing for guiding the movable stair section laterally to a position within the housing and concurrently to provide an opening intermediate the rear surface of the reflector and the movable section through which objects may be moved to selected positions and caused to appear in a location simulating that of floating above the stair section itself.

5. The arrangement claimed in claim 4 comprising, in addition, a rail section adjacent the end of each of the steps of each section and extending for substantially the full rise of the combined fixed and movable step sections, paneling sections between the said rail and the step sections, said paneling having angularly extending grooves extending outwardly from substantially the intersection of each riser and tread step section, and at least one of said grooves providing a guiding slot for guiding the reflector in its outward motion relative to the step sections.

6. A display unit comprising a staircase formed of at least one fixed section and at least one movable section each in the form of steps and arranged to be brought into substantially precise registration and alignment with one another so as to provide a continuous usable staircase, a support housing of which the fixed stair section is arranged to form at least a part of one outer surface and into which housing the movable stair section is adapted to be positioned, a support means for carrying the movable staircase section, a reflecting element positioned and supported within the housing in a plane forming substantially equal angles with intersecting adjacent tread and riser sections of the fixed and movable stair sections, respectively, means for moving the reflector element to a position such that it reflects the fixed stair section to give the illusion of the actual presence of the movable stair section, and guide and support means secured within the housing for guiding the movable stair section laterally to a position within the housing and concurrently to provide an opening intermediate the rear surface of the reflector and the fixed stair section through which objects may be moved to selected positions and caused to appear in a location simulating that of protruding above the stair section itself.

7. The arrangement claimed in claim 6 comprising in addition a rail section adjacent the end of each of the steps of each of the fixed and movable sections and extending for substantially the full rise of the combined step sections, paneling sections between each of the said rail and the step sections, said paneling having grooves extending angularly outwardly from substantially the intersection of each riser and tread step section to the rail to form a guiding slot for positioning and supporting the reflector in its outward motion relative to the step sections.

8. A display unit comprising a staircase formed of a plurality of fixed step sections and a movable step section, all of the step sections being similar and arranged to be brought into substantially precise alignment with one another so as to provide a continuous and usable staircase, a housing of which the fixed and movable step sections are normally arranged to form an outer surface and into which housing the movable stair section may be shiftably positioned to form thereby an opening in the housing, a reflecting element positioned and supported within the housing in a plane substantially between adjacent tread and riser sections of the fixed and movable step sections, respectively, means for moving the reflector element to a position such that it reflects the treads of the fixed step section to give the illusion of the actual presence of the risers of the movable step section, and guide and support means secured within the housing for supporting and guiding the movable step section laterally to a position within the housing and concurrently to provide an opening inter-

mediate the rear surface of the reflector and the fixedly positioned step section through which objects may be moved to selected positions and caused to appear in a location simulating that of suspension above the staircase at points intermediate the top and bottom thereof.

9. A display unit comprising a staircase having at least one fixed section and a movable section, each of the sections comprising a series of steps which each include tread and riser sections, and each of the movable and fixed sections being arranged to be brought and fixed substantially into precise registration and alinement with one another so as to provide a usable staircase section, said movable and fixed sections of steps each having tread and riser sections of substantially equal length and the combined staircase formed of the plurality of sections being arranged to rise at substantially an angle of 45° to a horizontal plane, a housing of which the fixed stair section is arranged to form at least a part of the outer surface and into which housing the movable stair section is adapted to be positioned, a support contained within the housing for carrying and supporting the movable stair section and permitting lateral shift thereof into the housing to separate the movable and fixed stair sections, a reflector member also supported within the housing and located to slide in a plane substantially normal to the angle of rise of the staircase and located at the junction of the tread and rise stair sections of the fixed and movable sections respectively, means to shift the movable step section laterally relative to the fixedly positioned steps by a distance substantially equal to that of the thickness of the reflecting member, means to semi-permanently fasten the movable step section in said position following the lateral shift in position, means to move the reflecting member intermediate the tread and rise section of the fixed and movable steps between which it is positioned along a plane substantially normal to that of the rise of the complete staircase, means to release the movable step section from its semi-permanently secured position with the positioning of the reflecting member in its extended position, and means to move the movable stair section laterally upon its guide and support means upon release from the semi-permanently secured position so that the shift of the movable step section uncovers an opening in the housing intermediate the rear surface of the reflector and the movable step section through which opening objects may be moved to selected positions relative to the fixedly positioned steps and the reflector so as to appear when viewed from the front of the reflector and the fixed steps as if floating in space above the steps.

10. The arrangement claimed in claim 9 comprising in addition a handrail section adjacent the end of each of the steps of each of the fixed and movable stair sections and extending for substantially the full rise of the combined fixed and movable sections, paneling sections between each of the said handrail and the step sections, said paneling having grooves extending angularly outwardly from substantially the intersection of each riser and tread element of each step and in a plane substantially coinciding with the plane of motion of the reflector, said groove which intersects the tread and riser members of the fixed and movable sections constituting a guiding slot for positioning and supporting the reflector in its outward motion relative to the step sections.

11. A staircase having at least one fixedly posi-

tioned step section and a movable step section located thereabove and arranged for positioning in substantially precise alinement therewith to form the complete staircase, a railing section adjacent the ends of each of the step sections and extending for substantially the complete length of the formed staircase, paneling members intermediate the said rail sections and the steps of the staircase and having grooved members therein extending between the junction of the tread and riser section of each step of the staircase at an angle of substantially 45° to each of the tread and riser members and extending for substantially the full distance between the said steps and rail section, means for moving the movable step section to a semi-permanently locked position inwardly from the fixed step sections a minute distance compared to the length of the step tread and riser sections for providing the opening between the lower fixedly positioned step section and the movable step section, a reflecting member positioned in a plane to correspond to the grooves in the paneling section, means for moving the reflecting element in the said groove member between the fixed and movable step section and outwardly from the fixed step section toward the railing so as to image the fixed step section and thereby to simulate the presence of the movable section, means operating to release the movable step section from its semi-permanently secured position at time periods when the reflecting member is moved to the position to image the said fixedly positioned step section, and means for slidably moving the movable step section in a direction inwardly from the said fixed step section to provide an opening behind the reflecting member through which objects may be moved to selected positions relative to the reflecting member and the fixed step section so as to simulate a position of floating above the fixed step section.

12. A staircase having a pair of fixedly positioned step sections and a movable step section located intermediate the said two sections in substantially precise alinement therewith to form the complete usable staircase, a railing section adjacent the ends of each of the step sections and extending for substantially the complete length of the staircase, paneling members intermediate the said rail sections and the steps of the staircase, said paneling having grooves therein extending between the junction of the tread and riser section of each step of the staircase and extending at an angle of substantially 45° to each of the tread and riser members for substantially the distance separating the said steps and rail section, means for moving the movable step section inwardly from the pair of fixed step sections a minute distance compared to the length of the step tread and riser sections for providing an opening between the lower fixedly positioned step section and the movable step section, means for semi-permanently locating the movable section in said last named position, a reflecting member positioned in a plane to correspond to the grooves in the paneling section, a fastening element supported in the paneling section groove coinciding with that whereat the reflecting element is supported, said fastening element being located at a point generally adjacent the railing, means for moving the reflecting element in the said groove member between the fixed and movable step section and outwardly from the fixed step section to substantially the location of the fastening element, means operat-

13

ing to release the movable step section from its semi-permanently secured position coincidentally with the positioning of the reflecting member substantially adjacent the said fastening member, means operable with release of the movable step section for slidably moving the said section in a direction inwardly from the two said fixed step sections to provide an opening behind the reflecting member through which objects may be moved to selected positions relative to the reflecting member and the fixed step section so as to simulate a position of floating above the fixed step section, and means for subsequently moving the reflecting member within the said grooves to a position closer to said railing than that of the initial location of said fastening members and concurrently moving the fastening

14

members within the grooves to a position closer to the railing section from which position said fastening member is adapted to return to normal position upon the removal of the said reflecting body from its protracted position.

JOHN P. CAHN.
